IRONING DEVICE

John Paul Ahlbrandt, Chicago, Ill., assignor to
 Borg-Warner Corporation, Chicago, Ill., a corporation of Illinois

Application October 11, 1937, Serial No. 168,365

7 Claims. (Cl. 38—66)

This invention relates to ironing devices, and particularly to the construction of the shoe portion thereof.

The heating portion of a continuous ironing device is generally comprised of a shoe or cloth contacting portion the surface of which must be smooth to avoid marking the cloth, a heating element, usually electrical, a backing plate for holding the heating element against the shoe, 10 and a cover. The assembly is generally bolted together by means of studs welded to the shoe and extending through the various units and cover, with nuts clamping the units together.

It has been found, however, that the weld at 15 the studs mars the surface of the shoe, that the studs are uniformly spaced only with difficulty, and that more metal is used in the shoe than is necessary for efficiently performing the functions of the ironer.

20 The object of this invention is an improved ironer shoe assembly which eliminates the stud bolts and their attendant surface marring.

Another object of this invention is a simplified construction of ironer shoe and cover which enables the shoe to be held in the cover by means 25 of a sliding fit.

Still another object is a reduction in the amount of metal required for the shoe.

Still another object is an ironer shoe having a 30 cooler leading edge to prevent burning the hands of the operator.

These and other objects of the invention will become apparent from the following description when taken together with the accompanying drawing which forms a part thereof, and in which—

Fig. 1 is a fragmental plan view of the novel shoe assembly with a portion cut away to expose the principal parts thereof; and

40 Fig. 2 is a side elevation in section of the assembly of Fig. 1.

In its preferred form this invention comprises a cover having in-turned edges, a shoe adapted to be slipped over the edges and between the 45 sides of the cover, and a spring-pressed backing plate the springs being in the form of strips spot welded to the backing plate and having upturned ends which are anchored in the upper corners of the cover. The leading edge is enclosed by 50 the cover and insulating material is packed between the cover and shoe to keep the temperature of the cover within safe limits.

Referring now to the drawing for a detailed description of the invention, 10 is an ironer shoe 55 which is curved along the major portion of its

area to conform to the shape of a rotating roll 11. Shoe 10 is preferably made from stainless metal, or is surfaced with stainless metal, to insure a clean working surface. Such stainless metal is considerably more expensive than ordinary metal and hence it is of advantage to use as little of the stainless metal as possible, i. e., to make the shoe as narrow as is conveniently possible. Adjacent shoe 10 is an electrical heating unit 12 which may be of any suitable construction, 10 the one illustrated being comprised of a mica or other heat resistant core 13 around which is spirally wound a flat ribbon 14 which possesses sufficient electrical resistance to become white hot when the usual electrical current is passed 15 therethrough. As a protection for the hot ribbon 14, mica or other inert sheets 15 are placed on each side of ribbon 14. Suitable leads 16 are brought out from the ribbon 14 to connect said ribbon with an automatic temperature controlling device 17 which is regulated by means of a handle 18 located exteriorly of the assembly, the handle engaging a shaft 18' removably secured to control 17.

Heating unit 12 is maintained in contact with shoe 10 by means of a backing plate 19 which is relatively heavy so that it will retain its shape under pressure. Said backing plate 19 is contoured to provide a uniform spacing between itself and shoe 10. A plurality of leaf springs 20 are spot welded to backing plate 19 at the center 21 thereof. Each spring is formed to have an initial contour such that when bent downwardly on either side of the weld, it will still clear backing plate 19. Thus by deflecting the free ends of the spring toward the shoe, pressure will be exerted upon backing plate 19 at the weld to maintain heating unit 12 against shoe 10, provided shoe 10 is held against motion in the direction of pressure.

40 The means for deflecting springs 20 and holding shoe 10 comprises a cover 22 preferably made from sheet steel and of the same width as the ordinary cover. Said cover 22 is formed with a curved upper surface 23, substantially parallel 45 sides 24 and 25 and inwardly and upwardly turned ends 26 and 27. Ends 28 and 29 of spring 20 are bent upwardly and are anchored in the corners formed by the junction of surface 23 and side 24, and surface 23 and side 25 respectively. 50 The edges 30 and 31 of shoe 10 are offset for a distance which is sufficient to enable said edges to contact edges 26 and 27 respectively of cover 22. The purpose of the offset is to remove edges 26 and 27 from the sphere of action of shoe 10. 55

It will be apparent now that the ends of springs 20 will be deflected toward shoe 10 by contact with cover 22, and that shoe 10 will be held from movement in the direction of pressure by the inturned ends of the cover.

5 For purposes of attaching the assembly to the remainder of the ironer mechanism (not shown) a bracket 32 is welded or otherwise secured to cover 22. Said bracket 32 may be provided with 10 an ear 33 having an aperture 34 through which a hinge pin may be passed.

The ends of cover 22 are closed off by means of removable plates 35 which are flanged and secured at the flanges to the cover by screws 36.

15 To disassemble the ironer shoe, end plate 35 is removed, handle 18 and shaft 18' are likewise removed, and the ironer shoe assembly is simply slid out from cover 22. Since no fasteners are used to hold back plate 19, heater element 12 20 and shoe 10 together, these parts separate as soon as they are removed from the cover.

It will be noted that both edges 30 and 31 of 25 shoe 10 are enclosed by cover 22. These edges take no part in the actual ironing, and hence need not be at ironing temperature. Conduction of the heat from the central portion of the shoe, however, causes these edges to become hot and hence the substantial enclosure of these edges by cover 22 protects the operator against 30 an inadvertent contact with such edges. In the form illustrated suitable strips of insulating material 31, 38 are inserted between cover 22 and the ends of shoe 10 to increase the temperature gradient from the shoe to cover 22, i. e., the temperature of cover 22 is still further reduced.

35 Since cover 22 is of substantially standard width, and since ironer shoe 10 fits within cover 22 instead of protruding beyond it as in previous designs, it is apparent that the width of shoe 10 40 is considerably reduced and hence a substantial economy of material is effected. No portion of the shoe is welded to other parts of the assembly, and hence the operative surface of the shoe can be made perfectly smooth.

45 It is understood that the foregoing description is merely illustrative of a preferred form of the invention, and that the scope of the invention, therefore, is not to be limited thereto but is to be determined by the appended claims.

50 I claim:

1. An ironer shoe assembly comprising an elongated shoe, a cover having side regions receiving the longitudinal edge regions of said shoe, and resilient means under compression between the 55 inner surfaces of the shoe and cover respectively, pressing the shoe against said side regions of the cover so as to fix the shoe in the cover.

2. An ironer shoe assembly comprising an elongated shoe, a cover having side regions receiving

the longitudinal edge regions of the shoe, and a plurality of leaf springs engaged under flexed distortion between opposed regions of the interior surfaces of the shoe and cover, whereby to press the shoe against said side regions of the cover so 5 as to fix the shoe in the cover.

3. An ironer shoe assembly comprising a shoe, a cover for the shoe having in-turned edges, said shoe being slideable relative to said cover upon said edges, and spring means between said cover and 10 shoe for holding said shoe against said edges, said spring means being likewise slideable relative to said cover.

4. An ironer shoe assembly comprising a shoe, a cover for the shoe having in-turned edges, said 15 shoe being slideable relative to said cover upon said edges, a heating unit adjacent said shoe, a rigid plate adjacent said unit, and resilient means between said plate and cover and slideable relative to said cover whereby to compress said plate, 20 unit and shoe against said edges, said resilient means, plate, unit and shoe being removable from said cover by sliding relative thereto.

5. An ironer shoe assembly comprising an elongated shoe, a cover for the shoe having in-turned 25 longitudinal edges, said shoe being slideable relative to said cover upon said edges, a heating unit adjacent said shoe, heat insulating means between said cover and shoe at the edges of the shoe, a rigid plate adjacent said unit, and leaf 30 springs secured to said plate and having ends slidably anchored in said cover, whereby to compress said plate, unit and shoe against said edges, said springs, plate, unit and shoe being removable 35 from said cover by sliding relative thereto.

6. An ironer shoe assembly comprising an elongated shoe, a cover having side regions terminating in inturned flanges receiving the longitudinal edge regions of said shoe, a heating unit adjacent 40 said shoe, a rigid plate adjacent said heating unit, and resilient means engaged under compression between opposed regions of the said plate and cover, and serving to fix all of the parts in their assembled relationship, said shoe being longitudinally slideable upon said flanges for disassembling 45 the parts.

7. An ironer shoe assembly comprising an elongated shoe, a cover having side regions terminating in inturned flanges receiving the longitudinal edge regions of said shoe, a heating unit adjacent the inner surface of the shoe, and resilient 50 means engaged under compression between opposed regions of said heating unit and the cover, and serving to maintain the parts in their assembled relationship, said shoe being slideable 55 longitudinally upon said flanges for disassembling the parts.

JOHN PAUL AHLBRANDT.
